DESIGN FOR A CARD HOLDER

Jerome E. Gillett, Superior, Wis.

Application May 28, 1945, Serial No. 119,773

Term of patent 7 years

(Cl. D74—1)

To all whom it may concern:

Be it known that I, Jerome E. Gillett, a citizen of the United States, residing at Superior, in the county of Douglas and State of Wisconsin, have invented a new, original, and ornamental Design for a Card Holder, of which the following is a specification, reference being had to the accompanying drawing, forming part thereof.

Fig. 1 is a top plan view of a Card Holder, showing my new design.

Fig. 2 is a front elevational view of Fig. 1,
Fig. 3 is a rear elevational view of Fig. 1, and
Fig. 4 is an enlarged perspective view of Fig. 1.

I claim:

The ornamental design for a card holder, substantially as shown.

JEROME E. GILLETT.
